UNITED STATES PATENT OFFICE.

WILLIAM H. BAZLEY, OF WHITMAN, MASSACHUSETTS.

ACETYLENE-GAS GENERATOR.

SPECIFICATION forming part of Letters Patent No. 699,645, dated May 13, 1902.

Application filed June 3, 1901. Serial No. 62,905. (No model.)

To all whom it may concern:

Be it known that I, WILLIAM H. BAZLEY, of Whitman, in the county of Plymouth and State of Massachusetts, have invented an Improvement in Acetylene-Gas Generators, of which the following description, in connection with the accompanying drawings, is a specification, like characters on the drawings representing like parts.

This invention relates to acetylene-gas generators, and has for its object to provide a supplemental carbid-holder within the bell, which is disposed below the air-outlet, whereby gas may be formed in the bell and the air driven out through said air-outlet and the chamber within the bell become filled with gas and the outlet-pipe become water-sealed before the first carbid-holder of the regular series comes in contact with the water; also, to provide the carbid-holders with sloping top walls, which protect the carbid from intimate association with the moisture contained in the gas and also direct the passage of the gas; also, to provide the carbid-holders with an outlet for the gas in open communication with a passage by which the gas is delivered to the top of the gas-chamber within the bell, and also to provide a chamber within the bell which is at all times in open communication with the atmosphere, which provides an outlet for the air contained within the bell when the apparatus is first charged and also an escape for the gas in case of overproduction.

Figure 1 shows in vertical section an acetylene-gas generator embodying this invention; Fig. 2 is a vertical section and partial elevation of the bell, showing the carbid-holders and support therefor; and Fig. 3 is a horizontal section of the bell shown in Fig. 1, taken 40 on the dotted line 3-3.

a represents the stationary tank, of cylindrical form, which is designed to be filled with water, and *b* is the bell, which is made of less diameter than the tank *a* and adapted to work up and down therein. The tank *a* has a main compartment *a'* and an auxiliary compartment *a''*, said compartments being formed by a division-wall *a''*, secured in place within the tank near the bottom. Centrally disposed 45 within the tank *a* is a vertical pipe *c*, which extends from the bottom to a point above the top of the tank, passing through both compartments thereof, and a pipe *c'* leads from said vertical pipe *c* at a point within the com-

partment *a''* out through the side wall of the tank, which is connected to a service-pipe *c'*, located outside of the tank. A pipe *d* is centrally disposed within the bell, which is made larger in diameter than the pipe *c*, so as to work up and down over said pipe *c* telescopically. The pipe *d* is made long enough to project down to a point substantially flush with the lower end of the bell, and as said pipe *c* projects above the tank it will be seen that the pipe *d* always incloses the upper end portion, at least, of the pipe *c*. The telescopic connection of the pipes *c* and *d* is at all times beneath the surface of the water contained in the tank *a*, so that a water seal is provided for the pipes at this point, insuring a gas-tight telescopic joint. The upper end of the pipe *d* is connected by a short pipe *d'* to the upper end of the bell, said short pipe *d'* projecting downward from the crown thereof, so that the pipe *d* is really connected to the crown 55 of the bell, and therefore moves up and down with said bell. The telescopically-connected pipes *c* and *d* serve to conduct the gas from the bell to the service-pipe.

e represents a diaphragm or plate horizontally disposed within the bell, which forms the top wall of the gas-chamber, and pipes *e'* are connected to said top wall, which pass upward for a short distance and are connected by pipes *e''* to the pipe *d'*, so that an open connection is established between the gas-chamber and the telescopic conducting-pipes *c d*. Herein I have shown two of these short pipes *e'*; but one or any other number may be provided.

f represents a cylinder which is centrally disposed within the bell *b* concentric to the pipe *d*, and said cylinder is made open at its lower end and closed by a plate *f'* at its upper end, and said cylinder is made long enough 95 to extend to a point near the lower end of the bell and up through the top wall *e* of the gas-chamber and into the chamber at the top of the bell above said gas-chamber. This cylinder serves as an air-chamber, and it is designed 100 and intended that it shall be at all times in open communication with the atmosphere, and to accomplish this result a vertical pipe *f''* is contained in the tank *a*, which is located beside the pipe *c* and which extends from at or near the bottom of the tank *a* up into the cylinder or air-chamber *f*. The pipe *f''* projects a short distance above the top of the

tank *a*, so that its upper end projects a short distance above the surface of the water contained in the tank *a*. The lower end of the cylinder *f* is immersed in the water in the 5 tank *a*, so that a water seal is provided between the cylinder or air-chamber *f* and the pipe *f*². The lower end of the pipe *f*² projects down into the lower compartment *a*² of the tank *a* and is provided at a point a short 10 distance below the division-wall *a*³ with an outlet *f*³ to the atmosphere. Thus the cylinder or air-chamber *f* is in open communication with the atmosphere at all times by means of the pipe *f*². In case of overproduction 15 of the gas within the bell the bell will be lifted to its most elevated position, and when in such position a hole 20 in the wall of the chamber *f* will be brought to a point above the water-level, and thereby an open communication established with the atmosphere 20 through the chamber *f* and pipe *f*².

The carbid-holders, a number of which will be provided, are arranged on a support which is herein shown as comprising two cylinders 25 *h h'*, arranged centrally one within the other with an annular space between them, and said tubular support is mounted upon and is free to slide up and down on the cylinder *f*, which serves as a guide therefor. The tubular support *h h'* has at its lower end a float *h*² of any suitable construction, which rests on the water contained in the tank *a*, or it may be immersed therein, according to the position of the bell. The upper end of the tubular support bears against the top wall *e* of the gas-chamber, so that as the bell descends said tubular support and parts attached to or connected with it will correspondingly descend. The carbid-holders each consist of a 35 box-like structure *i*, open at one end for the introduction of the carbid and having a sloping top wall *i'*. Each carbid-holder also has an opening at its inner end communicating with the annular space between the cylinders *h h'*—as, for instance, the cylinder *h* may form the inner wall of each carbid-holder, and said cylinder at such points may be cut open or punctured, as at *i*², to provide such an opening. The gas formed in the carbid-holders 45 thus passes therefrom into the annular space between the cylinders *h h'*. At the upper ends of the cylinders the annular space is left open, and consequently the gas which enters said space is free to pass up and out at 50 the top of the tubular support, thereby entering the gas-chamber of the bell at the top, which is an important feature. The gas formed in the carbid-holders is well laden with moisture, and by causing it to enter the 55 gas-chamber at the top the moisture is allowed to fall by gravity. By making the top wall of each carbid-holder sloping considerably, as shown, the moisture falling thereon has an opportunity to run off, and as a result 60 the carbid contained in each carbid-holder is not brought into so intimate association with the moisture as would otherwise be the case.

Furthermore, said sloping walls direct the passage of the gas to the openings *i*². The lowermost carbid-holder of the regular series 70 is located at a point just above the connection of a trap-pipe *f*⁴, to be described, with the gas-chamber, so that before said lowermost carbid-holder is immersed in the water said pipe *f*⁴ will be trapped or water-sealed. 75

The air-chamber *f* contains within it a trap-pipe *f*⁴, comprising a vertical portion extending from nearly end to end of the chamber in parallelism with the central pipe *d* and a **U**-shaped portion at its lower end. The trap-pipe *f*⁴ is open at both ends and is connected at its lower end only to the wall of the chamber *f* at a point a short distance above the lower end of said chamber, such point, however, being sufficiently above the lower end 85 of the chamber so as to be above the surface of the water contained in the tank *a* when the bell is in its elevated position, so that when first starting the apparatus the air contained in the bell or in the gas-chamber thereof can 90 be driven out through said trap-pipe. Open communication is thus established between the gas-chamber of the bell and the atmosphere until such time as the bell descends, so as to allow the water to enter the trap-pipe, 95 when the **U**-shaped portion thereof immediately fills, and thereby water-seals the pipe and closes the communication with the atmosphere previously established.

When first starting the apparatus, the gas-chamber within the bell is filled with air, and it is desirable to displace the air with gas with as little loss of gas as possible and without causing a temporary overproduction, and to accomplish this result a supplemental carbid-holder is provided, as *m*, which is attached to the tubular support *h h'* in the same manner as the other carbid-holders, so that the gas generated therein will be delivered to the gas-chamber at the top; but said carbid-holder *m* is located at a point below the lowermost carbid-holder of the regular series and also below the connection of the trap-pipe *f*⁴ with the gas-chamber, which, it will be understood, is an outlet from the gas-chamber to the atmosphere. Into this supplemental carbid-holder *m* a small quantity of carbid is placed, which will be sufficient to generate enough gas to fill the gas-chamber. This supplemental carbid-holder *m* is first immersed in the water, and as the gas is generated it rises and enters the gas-chamber at the top and drives the air out through the trap-pipe *f*⁴. This action continues until the gas-chamber becomes filled with gas, and then 105 the bell gradually descends and the outlet to the pipe *f*⁴ enters the water and said pipe becomes water-sealed, and the gas-chamber is then closed to the atmosphere. This occurs 110 previous to the first carbid-holder of the regular series entering the water.

It will be understood that but a small quantity of carbid is required for the production of sufficient gas to displace the air in the bell,

and consequently the supplemental holder will be supplied with but a small quantity, while the other carbide-holders will be supplied with as much as desired. I believe myself to be the first to employ a supplemental carbide-holder for the accomplishment of this result, and therefore do not desire to limit my invention to the particular construction of the carbide-holder when used for this purpose or to the construction of the other parts of the apparatus, so long as said supplemental carbide-holder is located below the outlet from the gas-chamber to the atmosphere.

I claim—

- 15 1. In an acetylene-gas generator, a stationary tank, a bell moving up and down therein having carbide-holders contained in the gas-chamber therein and connected to a tubular support, an air-chamber centrally disposed in the bell which serves as a guide for said tubular support, and said air-chamber being in open communication with the atmosphere but water-sealed at its lower end, and means for connecting said air-chamber with the gas-chamber when the bell is lifted, substantially as described.
- 20 2. In an acetylene-gas generator, a stationary tank, a bell moving up and down therein having carbide-holders contained in the gas-chamber therein and connected to a tubular support, an air-chamber centrally disposed in the bell which serves as a guide for said tubular support, and said air-chamber being in open communication with the atmosphere but water-sealed at its lower end, and a pipe connecting said air-chamber with the gas-chamber of the bell, normally closed by a water seal, substantially as described.
- 25 3. In an acetylene-gas generator, a stationary tank, a bell moving up and down therein having carbide-holders contained in the gas-chamber therein and connected to a tubular support, an air-chamber centrally disposed in the bell which serves as a guide for said tubular support, and said air-chamber being in open communication with the atmosphere but water-sealed at its lower end, and a trap-pipe contained in said air-chamber connected with the gas-chamber of the bell, substantially as described.
- 30 4. In an acetylene-gas generator, a stationary tank, a bell moving up and down therein having carbide-holders contained in the gas-chamber therein and connected to a tubular support, an air-chamber centrally disposed in the bell which serves as a guide for said tubular support, and said air-chamber being in open communication with the atmosphere but water-sealed at its lower end, and a trap-pipe contained in said air-chamber the lower end of which is connected with the lower part of the gas-chamber, which when closed by the water forms a water seal which closes the passage between the gas-chamber and the air-chamber, substantially as described.
- 35 5. In an acetylene-gas generator, a stationary tank and a bell working up and down therein having a gas-chamber, carbide-holders contained therein having sloping top walls for shedding the moisture, substantially as described.
- 40 6. In an acetylene-gas generator, a stationary tank, a bell working up and down therein having a gas-chamber, carbide-holders contained therein, a support therefor to which a float is attached and a conducting-passage leading from the carbide-holders to the top of the gas-chamber, substantially as described.
- 45 7. In an acetylene-gas generator, a stationary tank, a bell working up and down therein having a gas-chamber, carbide-holders contained therein, a tubular support to which said carbide-holders are attached consisting of two cylinders of different diameter contained one within the other to form an annular space between them, said tubular support having openings communicating with said carbide-holders and terminating at the top of the gas-chamber and its annular space being open at the top to thereby deliver the gas to the top of the gas-chamber, substantially as described.
- 50 8. In an acetylene-gas generator, a stationary tank, a bell working up and down therein having a gas-chamber, an outlet from the gas-chamber to the atmosphere, carbide-holders contained within the bell above said outlet and a supplemental carbide-holder contained within the bell below said outlet, substantially as described.
- 55 9. In an acetylene-gas generator, a stationary tank, a bell working up and down therein having a gas-chamber, a trap-pipe leading from the gas-chamber which is in open communication with the atmosphere, carbide-holders contained within the bell above said trap-pipe and a supplemental carbide-holder contained within the bell below said trap-pipe, substantially as described.
- 60 10. In an acetylene-gas generator, a stationary tank, a bell working up and down therein having a gas-chamber, carbide-holders contained therein having sloping top walls, a tubular support to which said carbide-holders are attached consisting of two cylinders of different diameter contained one within the other to form an annular space between them, said tubular support having openings communicating with said carbide-holders and terminating at the top of the gas-chamber and its annular space being open at the top to thereby deliver the gas to the top of the gas-chamber, substantially as described.
- 65 11. In testimony whereof I have signed my name to this specification in the presence of two subscribing witnesses.

WILLIAM H. BAZLEY.
